UNITED STATES PATENT OFFICE

WALTER HAHNEMANN, OF BERLIN-MARIENFELDE, GERMANY, ASSIGNOR TO C. LORENZ AKTIENGESELLSCHAFT, OF BERLIN-TEMPELHOF, GERMANY

ANTENNA FOR SHORT AND ULTRA-SHORT WAVES

Application filed June 20, 1930, Serial No. 462,487, and in Germany October 30, 1929.

As is well known, a directed reception of short and ultra-short waves by means of a frame antenna is not possible according to the present methods. This fact is to be attributed to the circumstance, that the laws otherwise recognized in the high frequency art, have not been considered in dimensioning the frame-antennæ used. It is known, that with a mean wave-length of for instance 400 metres usually a frame of about from 40 to 60 centimetres side length will be employed. With longer waves relatively larger frames are used, which with commercial stations in particular possess a side length of several metres. The tests mentioned and carried out with the available frames for mean wave lengths for the directed reception of short waves, showed that a directed reception was not possible.

The conviction, that a directed reception of such waves is not possible at all, must be attributed to said fact. By virtue of certain properties, short and ultra-short waves persist in covering much greater distances than do the waves employed in long wave transmission. Furthermore, short waves are not deviated from their straight line course as easily as are long waves. Because of these properties the shorter waves are particularly useful in transmitting direction signals to ships and airplanes. Commercial short wave sets now operate successfully on from about 25 down to 16 meter wave lengths. Thus it becomes important that an antenna arrangement for short wave reception having good directivity is found for use in short wave radio direction finders.

According to this invention, the dimensions of the frame or loop of such an antenna arrangement must be so chosen, that the side length is very small in comparison with the wave length, amounting to a maximum of one-tenth of the wave-length. Besides, the distance of the frame from the earth potential must be as large as possible, but at least one-half of the wave-length.

One mode of construction of the arrangement according to the invention is shown on the drawing by way of example.

That proportions of the dimensions are

concerned which are not customary nowadays, follows from the accompanying drawing in particular. The frame R is connected by way of a supply lead V of energy with the high frequency initial circuit of the apparatus G. The side length of the frame is to be one-tenth of the wave-length at the most, while the distance a amounts to at least one-half of the wave-length. This unusually great distance must be chosen, so that the capacity between the frame and the apparatus, which obviously must be considered also as earth potential, remains sufficiently small. This condition in particular is not observed in the former frames nor was it necessary there to observe such conditions, since the influence of the capacity within the range of mean and long waves is not decisive owing to the other dimensions of the high frequency circuits. The supply line for the energy is, in order to ensure a symmetry of the conditions, designed particularly as concentric conductor surrounded by a hollow conductor, or in the form of two conductors arranged within a metal hose or the like. For maintaining the conditions of symmetry it is also of advantage, to connect with the earth the secondary coil of the coupling device in the center, or to choose as coupling device some capacities, which on the one hand are connected to the supply line for the energy and on the other hand their center point is connected with the earth.

I claim:

1. An antenna arrangement for directive reception of short and ultra-short waves, comprising in combination an antenna loop having a side length not greater than one-tenth of the length of the wave to be received and an antenna lead having an effective vertical length not less than one-half the length of the wave to be received.

2. An antenna arrangement for directive reception of short and ultra-short waves, comprising in combination an antenna loop having a side length not greater than one-tenth of the length of the wave to be received, an antenna lead having an effective vertical length not less than one-half the

length of the wave to be received and a conducting shield surrounding said antenna lead and connected to earth potential.

3. An antenna arrangement for directive reception of short and ultra-short waves, comprising in combination an antenna loop having a side length not greater than one-tenth of the length of the wave to be re-

ceived, and an antenna lead comprising two conductors arranged within a conducting shield and adapted to effect a connection between the loop and an apparatus connected to earth potential, said lead having an effective vertical length of not less than half the length of the wave to be received.

WALTER HAHNEMANN.
